UNITED STATES PATENT OFFICE.

HENRY N. MCKAY, OF SAN FRANCISCO, CALIFORNIA, ASSIGNOR TO REMINGTON TYPE-WRITER COMPANY, OF ILION, NEW YORK, A CORPORATION OF NEW YORK.

TYPEWRITING-MACHINE.

1,394,632.

Specification of Letters Patent.

Patented Oct. 25, 1921.

Original application filed April 25, 1919, Serial No. 292,586. Divided and this application filed November 20, 1919. Serial No. 339,287.

To all whom it may concern:

Be it known that I, HENRY N. MCKAY, citizen of the United States, and resident of San Francisco, in the county of San Francisco and State of California, have invented certain new and useful Improvements in Typewriting-Machines, of which the following is a specification.

This invention relates to typewriting machines and more particularly those using a cylindrical platen.

The present case is a division of my application Serial No. 292,586, filed April 25, 1919, and relates more especially to means for controlling an auxiliary carriage-carried ribbon, and to means for preventing "back printing" from said ribbon.

My invention is shown, in the present instance, embodied in a cylindrical platen controlling machine used in bookkeeping and in which the work sheets can be inserted into the machine, and properly collocated, with great speed, convenience and accuracy and printing effected on one of said sheets with the aid of said auxiliary ribbon.

One of the main objects of my invention is to provide efficient auxiliary ribbon control mechanism which will aid materially in the production of a machine of the character specified. It should be understood, however, that the invention has a wide range of uses and is not limited to its embodiment in a machine such as that indicated above, but may be employed wherever available, and that certain features thereof may be employed without others.

A further object of my invention is to provide means of the character specified which are in the nature of attachments that may be readily applied to existing typewriting machines without modifying, or materially modifying, the structural features of said machines as they now exist.

To the above and other ends which will hereinafter appear my invention consists of the features of construction, arrangements of parts and combinations of devices set forth in the following description and particularly pointed out in the appended claims.

In the accompanying drawings wherein like reference characters designate like parts in the various views,

Figure 1 is a detail fragmentary right-hand end view, with parts sectioned away and parts omitted, of a carriage of a No. 11 Remington machine equipped with the devices of my invention. 55

Fig. 2 is a plan view of the same.

Fig. 3 is a view corresponding substantially to Fig. 1 but showing the ribbon frame 60 in abnormal or lifted position.

Fig. 4 is a view corresponding substantially to Fig. 1 but showing the parts as they appear when seen from the left-hand end of the carriage. 65

Fig. 5 is a detail fragmentary perspective view of a portion of the auxiliary ribbon carrying frame.

Fig. 6 is an enlarged detail fragmentary sectional view showing one of the controlling 70 devices and the cam with which it coacts.

In the drawings I have shown only so much of the No. 11 Remington machine as may be necessary to arrive at an understanding of my invention in its embodiment 75 therein.

In the present instance I have included the features of construction of this invention in a machine equipped with work sheet controlling devices of the character disclosed in 80 my above mentioned application, but have only shown such of those devices in the present case as may aid in arriving at an understanding of this invention.

For guiding the two work sheets in their lateral relation, a compound chute or paper table, designated as a whole by the reference numeral 1, is mounted on the carriage frame 2 behind the cylinder or platen 3, said chute having a main section 4, the width of the 90 ledger or inside sheet *a*, and a depressed section 5, the width of the statement sheet *b*. The sides 6 of the main section constitute side edge gages for the inside sheet *a*, whereas the side walls 7 of the depressed section 95 constitute side guides for the narrow, outside or statement sheet *b*.

In this machine it is frequently desirable to insert the statement sheet *b* around the cylinder or platen 3 from the rear, introducing the sheet in the depressed section 5 of the chute and securing it in position therein. Subsequently a ledger sheet *a* is introduced from the rear in the chute section 4 and is 100

fed around the cylinder without disturbing the statement sheet. The means for thus controlling the work sheets are disclosed in my above mentioned application but need not be specifically pointed out herein.

Means are provided which enable the work sheets to be fed around the platen from the rear without colliding with or fouling on the auxiliary ribbon 8 or its bail, frame, or carrier, designated as a whole by the reference numeral 9, and which enable the larger or wider inside work sheet *a* to feed invariably behind the auxiliary ribbon and the narrower or outside work sheet *b* to feed automatically and invariably in front of the auxiliary ribbon. In attaining these objects insertions of the work sheets are made when the carriage is at a predetermined point in its travel, say at the extreme end of its writing line, and by causing the ribbon bail to be lifted automatically when the inserting position of the carriage is reached, as will hereinafter more clearly appear.

The frame or carrier 9 for the auxiliary ink ribbon 8 includes, in the present instance, a rock shaft 10 mounted at its ends in bearings in brackets 11 secured to the front cross bar of the carriage at the ends thereof and projecting rearwardly therefrom. The rock shaft 10 carries a rearwardly extending, fixedly secured, arm 12 near each end thereof. An inwardly extending paper feed roller 13 is carried by each arm 12, and is adapted to bear against the platen near an end thereof and support the frame in normal position, as shown in Figs. 1, 2 and 5. Each arm 12 of the ribbon frame carries a depending and laterally extending ribbon guide 14 formed with a guide slot or opening 15 through which the ribbon 8 passes. A rock shaft 16 extends between and receives a bearing in the arms 12, and a guide pin 17 is fixed to and extends inwardly from each of said arms. From an inspection of Figs. 2 and 6 it will be seen that the shaft 10 is slabbed off on one side to provide a flat face 10^a. Two adjustable members, blocks or supports 18 are mounted on the shaft 10, the opening in each block to receive the shaft conforming to the cross section of the latter to cause the blocks and shaft to rock together. An upwardly extending arm, controlling member or contact device 19 is connected to a base 20 which is pivoted at 21 to the associated block or bearing 18, each of said blocks carrying one of these pivoted arms. Each arm carries an anti-friction roller 22 and is retained in its operative position, shown in full lines in Fig. 6, by a spring catch 23 secured to its block by screws 24. A fixed cam, designated as a whole by the reference numeral 25, forms part of a sheet metal bracket 26 which is secured about centrally of the machine to a fixed portion thereof. In the present in-

stance this bracket is secured in place to the bottom of the forward fixed carriage rail by screws 27. The cam 25, as shown, is a double cam comprising an inclined surface 28 at each end and an intermediate dwell 29 forming the high part of the cam. This construction is such that one of the anti-friction rollers 22 will ride forward on an inclined face 28 of the cam, preferably, at or near the limit of the movement of the carriage. This results in rocking the shaft 10 and swinging the ribbon carrier from the position shown in Fig. 1 to that illustrated in Fig. 3, where it is above the printing line.

Should the operator wish to render either or both of the arms or contact devices 19 ineffective to coact with the cam 25, and thereby render the automatic action inoperative at either one or both ends of the travel of the carriage, it is merely necessary to turn either or both of said arms to the dotted line position shown in Fig. 6, thus moving said arm or arms out of coöperative relation with the cam.

In order that the arms may be adjusted along the rock shaft 10, and thus vary the points in the travel of the carriage where they may coact with the cam, each block is tapped to receive a set screw 30, the inner end of which is adapted to bear against the face 10^a of the shaft and thus fix each block in the position to which it may be adjusted along the rock shaft.

By automatically lifting the auxiliary ribbon 8 a suitable distance above the printing line in the manner described, and as shown in Fig. 3, the two sheets *a* and *b* passing around the platen can pass one to the front and the other to the rear of said ribbon without touching it, allowing the ribbon to be received between the sheets.

While I have shown and described two arms or contact devices 19, only one such device may be provided if desired.

In order to cause the ledger sheet, or wider work sheet *a*, to pass invariably behind the auxiliary ribbon, means are provided to hold this sheet close to the platen during its feeding operation and thus guide its top edge on the platen side of the auxiliary ribbon. These ledger sheet controlling guides are here shown as peculiarly shaped strips 31 of spring steel attached to the forward edges of the two small deflector plates 32 at the ends of the platen and curved upward and toward the center thereof roughly following the curvature of the platen for a certain distance.

It will be seen that with the carriage in inserting position, for example at the extreme left-hand limit of its movement, the natural tendency of the top edge of the statement sheet *b* when inserted around the platen from the rear, is to project forward at a tangent on emerging from between the platen

and center deflector 33. To obtain the desired result of causing the statement sheet *b* to feed accurately on the forward side of the auxiliary ribbon I utilize this natural 5 tendency of the statement sheet and provide means for controlling it, so that it may afterward be brought into proper co-operative relation with the platen. This is done by providing two flat guide fingers 34 mounted on 10 collars 35 which are adjustable along, and rigidly fastened by means of set screws 36, to the rock shaft 16 carried by the ribbon carrying frame or bail 9. To one end of this rock shaft 16 is rigidly attached a crank arm 15 37. A pin 38 on the operating end of this crank arm is engaged in a cam slot 39^a in a rigid arm 39 fastened to the carriage frame. When the ribbon bail is automatically lifted the guide-finger shaft 16 is caused to rock 20 in its bearings a certain distance, and to return to its original position when the ribbon bail drops. The flat guide fingers 34 in the normal position are approximately horizontal and lie out of the way. When the carriage 25 is moved to the extreme left end inserting position and the ribbon bail lifts, these flat fingers 34 are caused to turn, their forward ends moving downward so as to receive the top or leading edge of the statement 30 sheet *b* as it emerges from between the platen and center deflector 33, and to guide said top edge upward, close to, and on the forward side of the auxiliary ribbon 8. The rearward ends of these fingers, when the ribbon bail 35 drops back to its normal operative position, serve to press back the upper or leading portion of the sheet *b* and maintain it close to the cylinder in the correct position for writing.

40 For the convenience of the operator in controlling the manifolding on the ledger sheet *a* a novel device is provided for lifting the auxiliary ribbon into a non-manifolding position, which position is intermediate the 45 normal manifolding or operative position of the ribbon at the printing line, and the completely lifted or inserting position of said ribbon. When the auxiliary ribbon is in this intermediate or non-manifolding position it 50 is lifted just far enough so that no part of it remains in the path of the type. Hence it follows that when said ribbon is in this position the operator can write headings or other data on the statement sheet *b* without having 55 the same manifold on the ledger sheet *a*.

This result is produced by means of a hand actuated slotted arm or lever 40 pivotally mounted at one end, as at 41, on the left-hand bracket 11. The slot 42 in the arm receives a pin 43 projecting from an upright arm 44 on the left-hand arm 12 of the bail 9. The slot in the arm 40 is peculiarly contoured, having a shoulder 45 therein which is so formed that when the slotted arm is 60 lifted by means of the finger piece at its 65 outer end, the walls of the slot coacting with the projecting pin 43 will cause the ribbon bail to lift far enough to prevent manifolding. And when the arm 40 is so lifted the said shoulder 45 in the slot will coact with 70 and support the pin 43, and consequently the bail 9 to which the pin is connected, in the desired non-manifolding position. The slotted arm 40 is provided with a spring 46 so designed that when the bail is lifted farther than this intermediate non-manifolding position, either by hand or automatically through the lifting cam 25, the pin will be 75 released from the supporting shoulder 45 in the slot, allowing the ribbon bail to drop back to its normal or manifolding position under the action of its returning springs 9^a.

If therefore the operator should temporarily lift the bail to the non-manifolding position and forget to again restore the bail to 80 the manifolding position after a heading is completed, a movement of the carriage either backward or forward to substantially the full extent of its movement will result in the bail being automatically returned to its 85 manifolding position before proceeding with the writing.

I have provided means in the present instance to prevent the auxiliary ribbon from "back printing" on the form in front of the 90 ribbon 8, in this case the statement sheet *b*. To avoid this back print previously, it was customary in some instances to employ a short strip of paper or other fabric which was fastened to the guide brackets of the 95 ribbon carrying bail by gluing or sewing the ends of the strip upon themselves. This means has always been extremely unsatisfactory, due to the short life of a non-adjustable short strip and the cumbersome and 100 awkward manner of replacing a worn strip with a fresh one. These difficulties in the way of eliminating back printing have been completely eliminated in the present invention through the novel use of an unlinked 105 shield ribbon 47 wound on a spool 48 mounted on a rigid arm 44 on the ribbon bail 9. The shield ribbon passes through suitable slots 47^a in guides 14 so as to follow a path 110 in front of the auxiliary ribbon 8 to a receiving spool 48 similarly mounted on the rigid projection 44 on the opposite side of the bail. The shield ribbon in passing from one spool 48 to the other passes over the headed 115 guide pins 17.

The double guide openings 15 and 47^a formed in the parts 14 of the ribbon carrying bail permit the auxiliary ribbon 8 and the shield ribbon 47 each to travel through its own guide openings or separate guides. 120 The shield ribbon feeding and receiving spools are equipped with pressure springs 49 designed to bear against and produce sufficient friction upon the spools to maintain them in whatever position they are 125 130

rotatively adjusted to, in spite of the constant lifting and falling of the auxiliary ribbon carrying bail. By this means a constant tension of the shield ribbon is assured 5 to maintain taut the stretch thereof between the two spools.

Whenever a certain portion of the shield ribbon, in protecting the backs of the statement sheet *b* from back printing, has absorbed sufficient ink to permeate the shield ribbon fabric, or when that section has become worn, the operator simply winds the shield ribbon from the feeding spool to the receiving spool far enough to bring a fresh 15 section of the shield ribbon fabric into use.

The feed of the auxiliary ribbon may be effected by any suitable means. In the present instance the feed is automatically effected as each line spacing operation by 20 the actuation of the line spacing handle 50 of the Remington machine. Thus the usual forwardly extending brackets 51 which project from the carriage and support a portion of the Wahl adding attachment, constitute 25 supports for angular brackets 52, the upright arms of which provide bearings for a shaft 53 which extends transversely across the machine and is thus supported by the carriage. This shaft has two 30 ribbon spools 54 loosely mounted thereon. One flange of each spool is provided with projections 55 with which a pivoted clutch member or lever 56 is adapted to engage to lock the associated spool to turn with the 35 shaft. A spring 57 engages one arm of each of the pivoted clutch levers and is adapted to hold it in either the engaging or disengaging position. The right-hand end of the shaft 53 carries a ratchet wheel 40 58 engaged by a spring 58^a to prevent backward rotation. An actuating pawl 59 is pivoted at 60 on a slide 61 adapted to move fore and aft of the machine. This slide is supported at one end by a headed pin 45 62 which passes through a slot 63 in the slide and fixed on the upright arm of the associated bracket 52. The opposite end of this slide is pivoted at 64 to the upper end of an arm of the usual bell crank 65 of the 50 line spacing mechanism. As the upper end of this lever moves rearwardly it will cause a corresponding movement of the slide, and an actuation of the feed pawl 59 to turn the shaft 53 and thus feed the ribbon. A coiled 55 spring 66 is connected at one end to the pawl 59 and at its opposite end to the slide 61 in order to maintain the engaging end of the pawl in coöperation with the ratchet wheel.

From the foregoing it will be understood 60 that each operation of the line spacing handle 50 is effective to turn the ratchet wheel one or more notches to effect a longitudinal feed of the auxiliary ribbon.

It will also be understood that the reversal 65 in the direction of the feed of the ribbon

is controlled by the clutch levers 56. Thus by releasing the clutch lever from the full spool and engaging the clutch lever associated with the empty spool, the ribbon will be wound from the full to the empty spool. 70

The above various but closely related novel devices constitute parts of what is now commonly termed a collating mechanism.

It should be pointed out that the above 75 described mechanism makes possible daily entry posting on "fold-over" form such as department store bills, etc., without the use of carbon.

By employing the fold-over form with the 80 fold at the bottom and with the top sheet or "bill" narrower than the bottom sheet or "charge", leaving a suitable margin at the right and at the left, these forms can be inserted speedily into this collating machine. 85

The above described ribbon bail control mechanism and feed control mechanism will cause the original or outside sheet *b* to feed automatically and invariably in front of the auxiliary ribbon and the duplicate or inside 90 sheet *a* in back of it.

The shield ribbon eliminates entirely the objectionable back printing from the bill.

For some kinds of work, including daily 95 entry postings on fold-over forms referred to above, no special chute is needed, and a standard paper feed and stock or standard deflector plate are used. The form is dropped into a standard style of chute of a requisite width upon a set of "end-guides" 100 preferably, and is fed in the usual manner to the desired writing line. As the carriage is returned to the beginning of the line to write the posting, the auxiliary ribbon drops into manifolding position. After the entry 105 is made the carriage is tabulated again to the end of the line and the fold-over form is pulled out of the machine bottom first.

Certain features disclosed herein are claimed in my above mentioned application 110 from which this case was divided.

Various changes may be made in the construction without departing from my invention and certain of the features thereof may be employed without others.

What I claim as new and desire to secure by Letters Patent, is:

1. In a typewriting machine, the combination of a carriage, an auxiliary ribbon carrying bail or member carried by said carriage, 120 and means for automatically lifting said bail or member at a predetermined point in the movement of the carriage.

2. In a typewriting machine, the combination of a carriage, an auxiliary ribbon carrying bail or member carried by said carriage, 125 and means for automatically lifting said bail or member at a predetermined point in the movement of the carriage and for automatically dropping said bail or member to 130

its normal position when the carriage is moved away from said point.

3. In a typewriting machine, the combination of a carriage, an auxiliary ribbon bail or member carried thereby, and means for automatically lifting the said bail or member at a predetermined point in the movement of the carriage, said automatically operating means including a device adjustable to determine the point in the travel of the carriage where said automatically operating means shall be effective.

4. In a typewriting machine, the combination of a carriage, a ribbon carrying bail or member carried thereby, automatically operating means for lifting said bail or member at a predetermined point in the travel of the carriage, and means operable at will for rendering said automatically operating means inoperative.

5. In a typewriting machine, the combination of a carriage, an auxiliary ribbon bail or carrier carried thereby, and manually operated means operable at will for moving said auxiliary ribbon carrier to and for positively locking it in a non-manifolding position just above the printing line, a further movement of the bail in the same direction being effective to free it from said locking means.

6. In a typewriting machine, the combination of a carriage, a ribbon carrying bail or member carried thereby, automatically operating means for lifting said bail or member at a predetermined point in the travel of the carriage, means operable at will for rendering said automatically operating means inoperative, and manually operating means operable at will for moving said ribbon carrying bail to and holding it in a non-manifolding position.

7. In a typewriting machine, the combination of a carriage, an auxiliary ribbon bail or carrier carried thereby, manually operated means operable at will for moving said auxiliary ribbon carrier to and holding it in a non-manifolding position, and automatically operating means for releasing the auxiliary ribbon bail or carrier from the position in which it is held by said manually operated means.

8. In a typewriting machine, the combination of a carriage, an auxiliary ribbon carrying bail or member carried by said carriage, and co-acting contact devices one carried by the carriage and operatively connected to said bail and the other carried by a fixed part of the machine, one of said devices being in the nature of a cam which coacts with the other device to automatically effect a lifting of the bail at a predetermined point in the travel of the carriage.

9. In a typewriting machine, the combination of a carriage, an auxiliary ribbon carrying bail or member carried by said

carriage, coacting contact devices one carried by the carriage and operatively connected to said bail and the other carried by a fixed part of the machine, one of said devices being in the nature of a cam which coacts with the other device to automatically effect a lifting of the bail at a predetermined point in the travel of the carriage, and means for affording a relative adjustment between said devices to predetermine the point in the travel of the carriage where said devices shall become effective to lift the bail.

10. In a typewriting machine, the combination of a carriage, an auxiliary ribbon carrying bail or member carried by said carriage, coacting contact devices one carried by the carriage and operatively connected to said bail and the other carried by a fixed part of the machine, one of said devices being in the nature of a cam which coacts with the other device to automatically effect a lifting of the bail at a predetermined point in the travel of the carriage, and means for affording a displacement of one of said devices to move it out of coöperative relation with the other device and thus render them inoperative.

11. In a typewriting machine, the combination of a carriage, an auxiliary ribbon carrying bail or member pivoted on said carriage, a contact device carried by said bail, and a coöperating contact device carried by a fixed part of the machine, one of said contact devices being in the nature of a cam by which the bail receives a pivotal movement at a predetermined point in the travel of the carriage.

12. In a typewriting machine, the combination of a carriage, an auxiliary ribbon carrying bail or member carried by and movable on said carriage, a contact device carried by said bail, means for affording an adjustment of said contact device in the direction of the travel of the carriage, and a cam which coacts with said contact device to move the bail on the carriage and which is carried by a fixed part of the machine.

13. In a typewriting machine, the combination of a carriage, an auxiliary ribbon carrying bail or member carried by and movable on said carriage, a contact device carried by said bail, means for affording an adjustment of said contact device in the direction of the travel of the carriage, a cam which coacts with said contact device to move the bail on the carriage and which is carried by a fixed part of the machine, and means which enable a relative displacement to be effected between said contact device and cam to render them inoperative one on the other.

14. In a typewriting machine, the combination of a carriage, an auxiliary ribbon carrying bail or member carried by said

carriage and including as a part thereof a rock shaft, a contact device carried by and adjustable along said rock shaft and fixed to turn therewith, and a coacting contact device 5 carried by a fixed part of the machine, one of said contact devices being in the nature of a cam, whereby said ribbon bail is automatically lifted at a predetermined point in the travel of the carriage, said point being 10 determined by an adjustment of the first mentioned contact device along said shaft.

15. In a typewriting machine, the combination of a carriage, an auxiliary ribbon carrying bail or member carried by said carriage and including as a part thereof a rock shaft, a support secured to said shaft to turn therewith, a contact device carried by and movable on said support into and out of operative position, and a co-operative 20 contact device carried by a fixed part of the machine, one of said contact devices being in the nature of a cam which is effective to swing the bail.

16. In a typewriting machine, the combination of a carriage, an auxiliary ribbon carrying bail or member carried by said carriage and including as a part thereof a rock shaft, a block carried by and adjustable 25 along said shaft and fixed to turn therewith, a contact device pivoted on said block to swing into and out of operative position, and a coacting contact device carried by a fixed part of the machine, said contact devices having a camming action one on the other to turn the rock shaft and swing the ribbon carrying bail and elevate the ribbon carried thereby above the printing line.

17. In a typewriting machine, the combination of a carriage, an auxiliary ribbon bail or carrier carried thereby, and manually operated means operable at will for moving said auxiliary ribbon carrier to and holding it in a non-manifolding position, said means comprising a hand actuated lever 40 with a pin and slot connection between said lever and carrier, one wall of the slot forming a locking shoulder against which the pin is adapted to seat itself to lock the bail in its elevated or non-manifolding position, a further upward movement of the bail freeing the pin from the locking shoulder and permitting the bail to return to normal position.

18. In a typewriting machine, the combination of a carriage, an auxiliary ribbon bail or carrier carried thereby, manually operated means operable at will for moving said auxiliary ribbon carrier to and holding it in a non-manifolding position, and automatically operating means for returning the 45 carrier to the manifolding position.

19. In a typewriting machine, the combination of a carriage, an auxiliary ribbon bail or carrier carried thereby, manually oper-

ated means operable at will for moving said auxiliary ribbon carrier to and holding it in a non-manifolding position, and automatically operating means for releasing the carrier from control of said manually operated means and allowing it to return to the manifolding position.

20. In a typewriting machine, the combination of a carriage, an auxiliary ribbon bail or carrier carried thereby, manually operated means operable at will for moving said auxiliary ribbon carrier to and holding it in an abnormal position, and automatically operating means controlled by the travel of the carriage for releasing the carrier from control of said manually operated means and allowing it to return to normal position.

21. In a typewriting machine, the combination of a carriage, an auxiliary ribbon bail or carrier carried thereby, manually operated means operable at will for moving said auxiliary ribbon carrier to and holding it in a non-manifolding position, a cam, and means controlled thereby during the travel of the carriage for releasing the carrier from control of said manually operated means and allowing it to return to manifolding position.

22. In a typewriting machine, the combination of a carriage, a ribbon carrier carried thereby for normally maintaining a ribbon at the printing line, and automatically operating means for actuating said carrier to move the ribbon to an abnormal position where the leading ends of two work sheets fed into the machine will pass to opposite sides of the ribbon.

23. In a typewriting machine, the combination of a carriage, a ribbon carrier carried thereby for normally maintaining a ribbon at the printing line, and automatically operating means for actuating said carrier to move the ribbon to an abnormal position where the leading ends of two work sheets fed into the machine will pass to opposite sides of the ribbon, and for returning the ribbon carrier and ribbon to normal position of the carriage in its line of travel determining when the carrier shall be moved to and held in the abnormal position and when they shall be returned to the normal position.

24. In a typewriting machine, the combination of a carriage, means carried thereby for carrying an auxiliary ribbon, means in the form of a long fabric or shield ribbon for eliminating back printing of the auxiliary ribbon on a worksheet, and means for maintaining indefinitely a section only of said shield ribbon in use.

25. In a typewriting machine, the combination of a carriage, means in the form of a strip of fabric or shield ribbon for eliminating back printing of the auxiliary ribbon on

- the work sheet, and two spools on which said shield ribbon is wound, each of which is maintained indefinitely in the position to which it is rotated and the length of shield ribbon in use may be changed when desired. 5
26. In a typewriting machine, the combination of a carriage, means carried thereby for carrying an auxiliary ribbon, means in the form of a strip of fabric or shield ribbon 10 for eliminating back printing of the auxiliary ribbon on the work sheet, two spools on which said shield ribbon is wound, and a tension spring co-operative with each of said spools to hold it in the position to which it 15 is rotated and to maintain taut the length of ribbon between said spools.
27. In a typewriting machine, the combination of a carriage, an ink ribbon carrier carried thereby and movable thereon to 20 move the ink ribbon to and away from the printing line, a shield ribbon to prevent "back printing", and spools which carry said shield ribbon and which are carried by said ink ribbon carrier.
- 25 28. In a typewriting machine, the combination of a carriage, an ink ribbon carrier carried thereby, automatically operating means for shifting said carrier to move the ink ribbon to and away from the printing 30 line, a shield ribbon in front of and parallel with the ink ribbon, and spools for said shield ribbon, said spools and shield ribbon being carried by and movable with said carrier when the latter is shifted.
- 35 29. In a typewriting machine, the combination of a carriage, a rotative platen carried thereby, means by which an auxiliary ribbon is carried by the carriage, and means for guiding the free leading ends of two 40 work sheets introduced into the machine in the rear of the platen to opposite sides of the auxiliary ribbon.
30. In a typewriting machine, the combination of a carriage, a rotative platen carried thereby, means by which an auxiliary ribbon is carried by the carriage, means for guiding the free leading ends of two work sheets introduced into the machine in the rear of the platen to opposite sides of said auxiliary ribbon, and automatically operating means for controlling a portion of said guiding means. 45
- 55 31. In a typewriting machine, the combination of a carriage, a rotative platen carried thereby, means by which an auxiliary ribbon is carried by the carriage, and adjustable guide fingers for guiding the leading edge of one of two superposed work sheets in front of the auxiliary ribbon. 50
- 60 32. In a typewriting machine, the combination of a carriage, a rotative platen carried thereby, means by which an auxiliary ribbon is carried by the carriage, adjustable guide fingers for guiding the leading
- edge of one of two superposed work sheets 65 in front of the auxiliary ribbon, and automatically operating means for causing said guide fingers to assume positions which are operative for the purpose specified and for moving them to inoperative positions. 70
33. In a typewriting machine, the combination of a carriage, a platen carried thereby, paper controlling means, means by which an auxiliary ribbon is carried by the carriage and adapted to be interleaved between superposed work sheets on the platen, and automatically operating actuating means for controlling said paper controlling means and auxiliary ribbon to cause a separation of the leading ends of the work 75 sheets and a lifting of the auxiliary ribbon from its normal operative position between said work sheets when the carriage reaches a predetermined point in its travel. 80
34. In a typewriting machine, the combination of a carriage, a platen carried thereby, paper controlling means, means by which an auxiliary ribbon is carried by the carriage and adapted to be interleaved between superposed work sheets on the 90 platen, and automatically operating actuating means for controlling said paper controlling means and auxiliary ribbon to cause a separation of the leading ends of the work sheets and a lifting of the auxiliary ribbon 95 from its normal operative position between said work sheets when the carriage reaches a predetermined point in its travel, said automatically operating means including an adjustable device whereby the point in the travel of the carriage where such means are automatically operated may be predetermined and varied at will. 100
35. In a typewriting machine, the combination of a carriage, a platen carried thereby, paper controlling means, means by which an auxiliary ribbon is carried by the carriage and adapted to be interleaved between superposed work sheets on the platen, automatically operating actuating means for 105 controlling said paper controlling means and auxiliary ribbon to cause a separation of the leading ends of the work sheets and a lifting of the auxiliary ribbon from its normal operative position between said work sheets when the carriage reaches a predetermined point in its travel, and means by 110 which said automatically operating means may be rendered inoperative. 115
36. In a typewriting machine, the combination of a carriage, a platen carried thereby, paper controlling means, means by which an auxiliary ribbon is carried by the carriage and adapted to be interleaved between superposed work sheets on the platen, automatically operating actuating means for 120 controlling said paper controlling means and auxiliary ribbon to cause a separation of 125

the leading ends of the work sheets and a lifting of the auxiliary ribbon from its normal operative position between said work sheets when the carriage reaches a predetermined point in its travel, said automatically operating means including an adjustable device whereby the point in the travel of the carriage where such means are automatically operated may be predetermined and varied at will, and means by which said

automatically operating means may be rendered inoperative.

Signed at San Francisco, in the county of San Francisco, and State of California this 12th day of November, A. D. 1919.

HENRY N. McKAY.
